T. A. McCREANOR

COMBINED LICENSE PLATE HOLDER AND ILLUMINATOR

Filed Dec. 30, 1921

Inventor
Thomas A. McCreanor

By

George E. Orey

Atty

UNITED STATES PATENT OFFICE.

THOMAS A. McCREANOR, OF SOUTH MANCHESTER, CONNECTICUT.

COMBINED LICENSE-PLATE HOLDER AND ILLUMINATOR.

Application filed December 30, 1921. Serial No. 525,861.

To all whom it may concern:

Be it known that I, THOMAS A. McCREANOR, a citizen of the United States, residing at South Manchester, in the county of 5 Hartford and State of Connecticut, have invented certain new and useful Improvements in Combined License-Plate Holders and Illuminators, of which the following is a specification, reference being had therein 10 to the accompanying drawings.

This invention relates to a new and improved combined license plate holder and illuminator and it is the principal object thereof to provide a neat and attractive 15 mechanism that will display upon a motor vehicle an illuminated registration number or other device.

A further object of the invention is to produce a simple and inexpensive device 20 and one that will be exceedingly effective for its designed purpose.

The improvements in the details and arrangement of parts will be apparent from an inspection of the accompanying drawings 25 in connection with the description hereinafter contained and wherein a preferred embodiment of the invention is disclosed for the purpose of imparting a full understanding of the same.

30 In the drawings wherein like characters of reference indicate like parts in both views,

Figure 1 is a front elevation of my improved device, a portion thereof being 35 broken away so as to disclose the construction of the interior; and

Figure 2 is a transverse sectional view thereof taken generally upon line 2-2 of Figure 1.

40 In the practice of my invention I provide a case 10 having outwardly flaring sides 11 which are secured at their corners by the angle iron 12 or the like.

This case is preferably made of metal 45 having reflective qualities or it may be coated interiorly with a paint or other material that will produce the same result. The sides 11 are flaring so as to reflect the light rays outwardly and away from the bottom of 50 the case.

Fixed in the case bottom are a plurality of lamp sockets 13 in each of which is held a lamp 14 by means of a bayonet joint or the like. In the drawings I have shown two

of such lights, but more or less may be used 55 as desired.

The case is secured to a fender 15 or other part of the motor vehicle by one or more brackets 16. The open side of the case 10 is provided with a closure member which 60 is constructed of a frame 17 having an opening 18 therein and provided upon its inner side with cleats 19 near and at the top and bottom thereof, which hold in position a glass plate 20.

65 The closure member is pivotally connected with the case 10 by one or more hinges 21 and is locked in its closed position by a spring clip 22. The plate 20 is of colored glass, usually red, and its inner 70 face is painted a dark color, except at such places as will leave uncovered portions of the plate in the form of letters, numerals or the like as may be designed to be exposed. In the drawings the letters and numerals 75 so designed for exposure being "20-389 Conn-1921." Of course, any other arrangement of letters, numerals or the like may be substituted.

As shown, at the right of Figure 1, the 80 end of the plate 20 engages the adjacent wall 11 of the case 10, so as to be held thereby against movement in the cleats, the latter having open ends so that the plate can be slid into the cleats from either end of the 85 latter. The left hand end of the case 10 similarly engages the corresponding end of the plate 20.

By means of this device the registration 90 number, etc. is always displayed at night in bold, readily observable numerals and letters.

There are minor changes and alterations 95 that may be made within my invention aside from those herein suggested and I would therefore have it understood that I do not limit myself to the exact construction herein shown and described, but claim all that falls fairly within the spirit and scope of the appended claim.

100 What I claim as new and desire to secure by Letters Patent, is:-

In a combined license plate holder and illuminator, a casing having a back, sides, and fixed ends which latter flare outwardly, a closure member for the front of the casing hinged at a side thereof to the casing and composed of an open frame, engaged

with the front edges of the casing, inwardly extending cleats carried by the top and bottom of the frame, a license plate in the cleats, the license plate being of such length so that when the frame is in closed position the flared ends of the casing will engage the ends of the license plate to hold the latter

in the cleats, and said cleats having each of their ends open to allow the license plate to be slid into the cleats from the ends of the latter.

In testimony whereof, I have hereunto affixed my signature,

THOMAS A. McCREANOR.
